CLAIM

The ornamental design for a display screen with graphical user interface, as shown and described.

DESCRIPTION

FIG. 1 is a front view of a first embodiment of a display screen with graphical user interface;

FIG. 2 is a front view of a second embodiment thereof; and, FIG. 3 is a front view of a third embodiment thereof.

The outermost broken line perimeter illustrates a display screen and forms no part of the claimed design. The remaining broken lines illustrate portions of a graphical user interface and form no part of the claimed design.

The portions of FIGS. 1-3 shown in patterns of dense downward-right sloped solid lines, cross-hatched horizontal and vertical solid lines, and both combined, illustrate areas of three distinct contrasting appearances which form a part of the claim.
